TOY MUSICAL INSTRUMENT

Gustave Proll, Newark, N. J.

Application January 31, 1947, Serial No. 725,656

2 Claims. (Cl. 84—375)

1

This invention relates to improvements in wind musical instruments of the tuned reed type; and the invention has reference, more particularly, to toy musical instruments of the tuned reed type in the form of a clarinet or similar style of instrument.

The invention has for an object to provide a novel, simple and easily produced and assembled means for mounting a succession of tuned reeds within the tubular body of a toy instrument so that the same are operatively positioned relative to the sound emission apertures of said body; said mounting means being so characterized as to space the supported reeds away from the sound emission apertures of the body, and also so as to provide therein a resonance chamber between each so spaced reed and the sound emission aperture of the body to which the reed is related.

The invention has for another object to provide a novel carrier member or bar having longitudinally spaced, perpendicular openings therethrough corresponding in number and positions to the number and positions of the spaced sound emission apertures with which the body of the instrument is provided; said carrier member or bar having a slideway in its bottom or under face portion into which can be slidably entered a reed supporting plate provided with a plurality of tuned reeds, which are attached to said plate in longitudinally spaced relation corresponding to the spacing of the openings of said carrier member or bar; said reed supporting plate being adjustably positioned in assembled relation to the carrier member or bar so as to dispose the respective reeds beneath and across said respective openings of the latter; and the top face of said carrier member or bar being adapted to be sealed to the inner side of the tubular body of the instrument, whereby to align the openings of said carrier member or bar with the sound emission apertures of the instrument body.

Other objects of this invention, not at this time more particularly enumerated, will be understood from the following detailed description of the same.

An illustrative embodiment of this invention is shown in the accompanying drawings, in which:

Fig. 1 is a longitudinal sectional view of a toy musical instrument of the tuned reed type constructed according to the principles of this invention; Fig. 2 is a cross sectional view of the same, taken on line 2—2 in Fig. 1, but drawn on an enlarged scale.

Fig. 3 is a fragmentary top or plan view of the reed carrier member or bar with the reed sup-

2

porting plate operatively assembled therewith; and Fig. 4 is a longitudinal sectional view thereof, taken on line 4—4 in Fig. 3.

Fig. 5 is a fragmentary perspective view of the reed carrier member or bar and the reed supporting plate in disassembled relation, but relatively positioned ready to be assembled.

Similar characters of reference are employed in the above described views, to indicate corresponding parts.

Referring to the drawings, the reference character 10 indicates the tubular body portion of a toy instrument of the clarinet type, to one end of which is affixed a mouth piece 11 having an axial passage 12 through which air may be blown into the interior of said body portion. The opposite end of said body portion 10 is closed by an end plug 13, the outer portion 14 of which is suitably formed to simulate the bell-shaped mouth of a wind instrument, such as one of the clarinet type. Said tubular body portion 10 is provided with a plurality of longitudinally spaced sound emission apertures 15. Manipulatable mechanical stop means of any well known construction may be employed to normally close the sound emission apertures 15, or said apertures may be closed and opened merely by application of the player's fingers thereto. An illustrative form of manipulatable mechanical stop means, as shown, comprises a base plate 16 which is suitably secured to the exterior of the body portion 10 adjacently parallel to the row of sound emission apertures 15. Struck up from said base plate 16 are fulcruming ears 17 to cooperate with corresponding hinge ears 18 with which the finger levers 19 of the aperture stop members 20 are provided. Said fulcruming ears 17 and hinge ears 18 are pivotally joined by a hinge pintle wire 21 arranged to extend therethrough. Spring means 22 is provided in operative relation to each finger lever 19 whereby to yieldably turn the same about its pivotal connection so as to normally hold the stop member 20 in closed relation to the sound emission aperture served thereby. The inner sides of the stop members 20 are preferably faced with a relatively soft sealing pad 23 of suitable material, such e. g. as felt, whereby to assure closure of the engaged sound emission aperture against outward passage of air therethrough. By selectively pressing upon the free end portions of the finger levers 19, the stop members 20 may be moved to aperture uncovering position as required.

The novel means according to this invention for holding and positioning a plurality of tuned reeds

within the interior of the instrument body portion 10 and beneath the sound emission apertures 15 of the latter comprises a rigid carrier member or bar 24 of substantial thickness and of suitable width and length. Said carrier member or bar 24 is provided with a plurality of longitudinally spaced, perpendicular openings or chambers 25 which extend therethrough between its bottom and top sides or faces. Said openings or chambers 25 correspond in number and positions to the number and positions of the sound emission apertures 15 of the instrument body portion 10. Provided in connection with the bottom or underside of the carrier member or bar 24 is a longitudinal slideway. Said slideway is formed by preferably integral beads 26 which respectively depend from the longitudinal marginal portions of the carrier member or bar. The inner sides of said beads 26 are provided with longitudinally extending, endwise open guide channels 27 which are bounded at their upper sides by the under face of the carrier member or bar and at their undersides by ledges 28. The upper face of the carrier member or bar 24 is transversely curved or arched to provide the same with a convexity adapted to conform to the concavity of the interior wall surface of the tubular body portion 10 of the instrument. The under face of carrier member is preferably flat.

The reference character 29 indicates a reed plate. This reed plate comprises a, preferably metallic, rectangular flat strip or plate of a width to correspond to the width of the slideway with which the under face of the carrier member or bar 24 is provided, and of a thickness to fit the guide channels 27 of said slideway. Said reed plate 29 is provided with a plurality of longitudinally extending air passage slots 30 which correspond in number and spacing to the number and spacing of the openings or chambers 25 of the carrier member or bar 24. Affixed to the underside of the reed plate 29, by riveting or otherwise suitably securing the same thereto, are the butt portions 31 of vibratory reeds 32. Said reeds 32 are respectively registered in alignment with the respective air passage slots 30, so as to be vibrated with musical tone producing effect, when air is permitted to pass upwardly through said slots.

To operatively assemble the reed plate 29 with the carrier member or bar 24, said reed plate is slid endwise, reed side down, into and through the slideway of the carrier member or bar, so that the longitudinal marginal portions of the reed plate engage in the guide channels 27 of said slideway. Since the slideway is contiguous to the underface of the carrier member or bar 24, the flat upper face of the reed plate, when said reed plate is entered in and supported by the slideway, will abut said flat underface of the carrier member or bar, whereby, when the reed plate is positioned so that its respective air passage slots 30 register in alignment with the respective openings or chambers 25 of the carrier member or bar, there can be no intercommunication of air between the respective sets of thus related air passage slots 30 and openings or chambers 25.

The carrier member or bar 24 having the reed plate 29 operatively assembled therewith is entered within the tubular body portion 10 of the instrument before the mouth piece 11 and end plug 13-14 are applied to the ends of the latter. The entered carrier member or bar is disposed with its upper convex face abutted against the concave interior wall surface of the body portion 10 and is longitudinally adjusted to bring its

respective openings or chambers 25 into operative opposed and aligned relation to the air emission apertures 15 of said body portion, whereupon the same is affixed to the body portion against shift or displacement by any suitable means, but preferably by gluing or cementing the same to said body portion. Since the upper convex face of the carrier member or bar conforms to the concavity of the interior wall surface of the body portion, after said carrier member or bar is fixed in place, the same will be sealed to the body portion 10 so as to prevent intercommunication of air between the upper ends of the openings or chambers 25, so that air can vent from the respective openings or chambers 25 only through the particular air emission apertures 15 of the body portion to which they are operatively related.

Since the carrier member or bar 24 is of substantial thickness, the reeds supported at the underside thereof are spaced a substantial distance from the corresponding air emission apertures 15 of the body portion of the instrument, and so that the openings or chambers 25 of the carrier member or bar are interposed between said reeds and the air emission apertures. As a consequence of this, individual air columns are provided in said openings or chambers 25 between each reed and its corresponding air emission aperture, whereby resonance is added to the sound waves generated by the air stream vibrated reeds.

By the above it will be understood that, from the standpoint of manufacturing production, the novel assembly of carrier member or bar and reed plate provides a very quick and easy means for introducing the series of tuned reeds into and operatively mounting the same relative to the tubular body of the instrument, which is calculated to save considerable time and labor in the assembling of the instrument parts; and, furthermore, from the standpoint of sound production and emission in use of the instrument, the tones of the reeds are greatly improved due to the provision of the openings or chambers of the carrier member or bar, whereby resonance inducing spaces are provided between the reeds and the air emission apertures of the instrument body portion.

Since changes could be made without departing from the scope of this invention as defined by the here following claims, it is intended that all matter contained in the foregoing description or shown in the accompanying drawings shall be interpreted as illustrative and not in a limiting sense.

I claim:

- 55 1. A toy musical instrument comprising a tubular body closed at one end and having a mouthpiece at its opposite end, said body having a plurality of spaced air emission apertures therealong, a carrier member of substantial thickness, 60 said carrier member having a transversely convex top surface conforming to and sealed to the concave interior surface of said tubular body beneath the air emission openings thereof, said carrier member having a flat under face and being provided with longitudinal resonance chamber forming openings of substantial depth extending between its under and top sides, said openings being spaced correspondingly to the spacing of said body apertures respectively for 65 communication therewith, slideway means contiguous to and extending along the said flat under face of said carrier member, and a flat reed plate having a plurality of longitudinally disposed tuned reeds spaced therealong, said reed plate being slidably entered in said slideway means so

as to be disposed in face to face abutment against the said flat under face of said carrier member with the reeds respectively resonance aligned with the bottom ends of the resonance chamber forming openings of said carrier member, whereby adjacent resonance chambers are sealed against intercommunication.

2. A toy musical instrument comprising a tubular body closed at one end and having a mouthpiece at its opposite end, said body having a plurality of spaced air emission apertures therealong, a carrier member of substantial thickness, said carrier member having a transversely convex top surface conforming to and cemented to the concave interior surface of said tubular body beneath the air emission openings thereof, said carrier member having a flat under face and being provided with longitudinal resonance chamber forming openings of substantial depth extending between its under and top sides, said openings being spaced correspondingly to the spacing of said body apertures respectively for communication therewith, said carrier member having opposed channeled guide portions independently extending along the margins of its said flat under face with the channels thereof contiguous to the said under face of the carrier mem-

ber, and a flat reed plate having air passage slots longitudinally spaced therealong and vibratory reeds affixed thereto with their free end portions registered over said slots, said reed plate being slidably entered in and between said guide portions so as to be disposed in face to face abutment against the said flat under face of said carrier member with the reeds respectively longitudinally aligned with the bottom ends of the resonance chamber forming openings of said carrier member, whereby adjacent resonance chambers are sealed against intercommunication.
